UNITED STATES PATENT OFFICE.

HENRY A. STEARNS, OF PAWTUCKET, RHODE ISLAND.

IMPROVEMENT IN RAILROAD-GATES.

Specification forming part of Letters Patent No. 173,823, dated February 22, 1876; application filed January 10, 1876.

To all whom it may concern:

Be it known that I, HENRY A. STEARNS, of Pawtucket, in the county of Providence, State of Rhode Island, have invented new and useful Improvements in Railroad-Gates, being an improvement on the patent to J. S. Winsor, May 26, 1874, No. 151,260; and I do hereby declare that the following is a full, clear, and exact description of the same, reference being had to the accompanying drawings, forming part of this specification.

Figure 1 is an elevation, showing the gate as seen from the railroad. The gate-bars are shown perpendicular, the gate being open, the position of the bars when the gate across the railroad is closed being shown in broken lines. Fig. 2 is an elevation, showing the gate as seen from the common road crossing the railroad. The gate is shown closed both across the common road or street and the sidewalks on each side of the same while the bars for closing the railroad are raised. Fig. 3 is a plan view, showing the position of the standards and the gates. The road or street and the sidewalks are shown closed, and the railroad open. When the road or street and sidewalk gate-bars are closed the gate across the railroad will be closed. Fig. 4 is a sectional view of one of the standards. Fig. 5 is a vertical section of one of the standards, showing the novel arrangement for operating three gate-beams so as to raise one when the other two are closed, and vice versa.

Similar letters of reference indicate corresponding parts.

This invention has reference to that kind of gates in which gate-bars swinging vertically are supported on shafts placed in standards and connected by chains, ropes, or wire rods; and consists in the novel arrangement by which both the road or street and the sidewalks are closed at one operation, either on one side of the railroad only or on both sides of the same. It further consists in the peculiar arrangement by which, when the gates protecting the railroad-crossing are open, a gate closes the railroad so as to prevent cattle from getting onto the road-bed; and also consists in providing strong and firm supports for the gate-bars, as is more fully set forth herein-after.

In the drawings, *a a a a* are four standards, within which suitable shafts, gears, and pulleys are so arranged as to move the several arms of the several gates. These standards *a a a a* are placed into the four angles formed at the crossing of a street or common road over a railroad, as shown in Fig. 3, where a road is shown crossing the railroad at a right angle. The road or street may cross the railroad at any other angle. *b b b b* are gate-bars, by which the approach to the railroad is prevented when the other gate-bars are raised. The gate-bars *b b* are connected with the shaft of the other gate-bars by means of beveled gears or segments of such gears. *c c c c* are gate-bars for closing the approach to the railroad when trains are passing over the same. These gate-bars swing vertically in a line parallel with the line of the railroad while the bars *b b* swing across the railroad and on a line with the line of the road or street crossing the railroad. The arms or gate-bars *c c* are secured to shafts supported in bearings in the standards *a a a a*. On these, shaft-pulleys or segments of pulleys are secured. These pulleys are connected by means of chains, ropes, or wires, so that the motion of one of the gate-bars *c c* is communicated at once to the others, and all move simultaneously. *d d d d* are the gate-bars, extending, when closed, over the sidewalk. These bars turn on a stud or pin, and are provided with segmental gears engaging with similar segmental gears at the end of the bars *c c*, so that when the bars *c c* are raised the bars *d d* are also raised. *e e* are balance-weights, arranged to balance or nearly balance the weight of the gate-bars. These weights *e e* may be placed on each bar, or a heavier weight may be placed on any one of the bars connected with each standard, so as to balance or nearly balance the weight of all the bars connected with one standard. *g g* are two bevel-gears, or they may be segments of such gears, as the gate-arms traverse only one-fourth of a circle. One of these bevel-gears *g* is connected with the shaft carrying the gate-bar *c*, and the other to the gate-bar *d*. When, therefore, the gate-bar *c* is raised the gate-bar *d* is lowered, and, as all the gate-bars *c c c c* are connected so as to move simultaneously, all the bars *d d d d* will be raised and

stand vertically when the gate-bars *c c c c* are lowered and the gate is closed.

The gate-bars *d d d* are to be painted of some bright color, so that when standing erect they will form a signal by which the engineer of an approaching train is assured that the gate at the crossing is closed, whereas he is warned of the danger when the gate-bars *d d* occupy a horizontal position, thus adding materially to the safety of railroad-travel.

In balanced vertically-swinging gates the bars are secured to the shaft on which they swing by the rotation or partial rotation of the shaft. When these shafts are perfectly straight all the gates will operate with little exertion of power. As soon, however, as the shafts, or either one of them, is bent, the gates not only require more power, but the connections are liable to break or get out of order. As the gate-bars are secured to the projecting portion of the shaft outside of the standard, any pressure at the free end of the gate-bar is liable to so bend the shaft.

To prevent the bending of the shaft I place suitable brackets *h h* on the standards, arranged so as to firmly hold the gate-bars either in the vertical or horizontal position, so that all strain, either from pressure or from high winds, will be sustained by these brackets, and not by the shaft. By these means

great strength is secured, and the shafts carrying the gate-bars are not liable to be bent.

Having thus described my invention, I claim as new and desire to secure by Letters Patent—

1. The combination, with the gate-bars *c c*, swinging vertically, of the bars *d d*, connected with the same by means substantially as described, so that both bars are raised and lowered simultaneously, as and for the purpose set forth.

2. The combination, with the bars *c c*, of the bars *b b*, connected with the same and operated by means substantially as described, so that when one set of these bars is raised the other set is lowered, as and for the purpose specified.

3. In a railroad-gate, the combination, with the bars *c c c c* for closing the approaches to the track, with the bars *d d d d* for closing the sidewalks, and the bars *b b b b* for closing the track when the others are open, and acting as safety-signals when raised, the whole operating together by means substantially as described, as and for the purpose herein set forth.

HENRY A. STEARNS.
